UNITED STATES PATENT OFFICE.

JOHN KIRBY, JR., OF DAYTON, OHIO, ASSIGNOR TO THE DAYTON MANUFACTURING COMPANY, OF DAYTON, OHIO.

DESIGN FOR A HANGING LAMP-FIXTURE.

45,463.

Specification for Design.

Patented Mar. 24, 1914.

Application filed January 23, 1914. Serial No. 813,995. Term of patent 7 years.

To all whom it may concern:

Be it known that I, JOHN KIRBY, Jr., a citizen of the United States, residing at Dayton, county of Montgomery, and State of Ohio, have invented a new, original, and ornamental Design for Hanging Lamp-Fixtures, of which the following is a specification.

The design is illustrated in the accompanying drawing, to which reference is made, and in which the design is shown in full perspective.

The fixture is of the contour shown in the drawing, comprising a supporting hanger, whose upper end is adapted to be secured to a ceiling, and whose lower end carries a translucent shade, a plurality of outwardly

and inwardly curved arms depending from the lower end of the supporting hanger and supporting, at or near their lower extremities, a base, which in turn supports a holder carrying a translucent globe. The shade and globe, together with the holder for the latter are represented in dotted lines for the purpose of illustrating their relation to the lamp fixture, but they form no part of my design therefor.

I claim:

The ornamental design for a pendent lamp fixture, as shown and described.

JOHN KIRBY, JR.
